UNITED STATES PATENT OFFICE.

WILLIAM E. EDWARDS, OF LESTERSHIRE, NEW YORK.

MACHINE-BRAKE.

1,216,424.

Specification of Letters Patent. Patented Feb. 20, 1917.

Application filed October 15, 1915. Serial No. 56,033.

To all whom it may concern:

Be it known that I, WILLIAM E. EDWARDS, a citizen of the United States, residing at Lestershire, in the county of Broome and State of New York, have invented certain new and useful Improvements in Machine-Brakes, of which the following is a specification.

My invention relates to an improvement 10 in safety brakes for sole leather cutting machines in which an upper and lower brake is applied to the drive wheel of the cutting machine and operated by a tread and it has for its object to provide a safe, simple and 15 automatically applied brake mechanism to the driving gear of sole leather cutting machines to guard against a repeat movement of the hammer. It is to be noted that in the operation of leather cutting machines 20 there is great danger from a repeat movement of the hammer caused by the second revolution of the driving gear after the cut has been made and thereby endangering the 25 hands of the operators in manipulating the cutting die in the machine.

With this object in view my invention consists in certain novel features of construction and arrangement of parts as will be hereinafter fully described and pointed 30 out in the claims, reference being had to the accompanying drawings in which Figure 1 is a side elevation of my device. Fig. 2 is a front elevation of a fragmentary part of my device. Fig. 3 is a plan view of a fragmentary part of my device. Fig. 4 is an end view in cross section of a part of my device. Fig. 5 is a front view of a fragmentary part of my device. The same reference 35 characters denote like parts in each of the 40 several figures of the drawings.

In carrying out my invention I have the cutter frame A and upon it the cutter A'. Mounted in the same I have the drive wheel B; also I have the lower brake shoe C and 45 pivotally mounted on the rear end of brake shoe C by the pivot 3 I have the upper brake shoe D. At the outer end of D I have the foot projection E having in it the slot 4. Mounted in slot 4 I have the turn screw 4' 50 which enters plate y beneath shoe E. The lower brake shoe C extends outwardly in the lever formation 5. Mounted on shoe E I have the parallel coil springs 6. 6 connecting with the lever projection 5 of shoe C. 55 Mounted on the inner side of the brakes C and D I have the lining 7 of leather or

other yielding material fastened to the brake D by means of the rivets 8. 8.

Horizontally mounted in the front of frame A by means of supports 8'. 8' I have the shaft 9 and horizontally extending from said shaft 9 projecting inward I have the lever arm 10 and on the outer end of shaft 9 I have the lever arm 11 projecting outward in the end of which is mounted the roller 12. Pivotally mounted on the lever 10 I have the socket 10' and on bar 14 I have pivotally mounted socket 10'' and the rod 13 threaded on each end extending downward has threaded connection with these sockets and thus is pivotally connected with the foot bar 14 and thus makes the foot tread adjustable and the movement of lever 11 adjustable as to distance. Mounted on the bars 14. 14 I have the foot tread 75 15. Attached to frame A I have the coil spring 13' extending down to and connecting with tread 15 and which supports tread 15. The bar 14 at its inner end is pivotally mounted in any convenient manner on the support 16. Projecting from the brake 6 I have the lug 17 which is mounted upon the vertical support 18, which in turn is mounted in the tread bar 14. In normal position the brake shoe linings 7, 7 contact with the 80 fly wheel B.

In the operation of my device when I desire to operate the cutting machine or to have the drive wheel of the cutter revolve I press down upon the footboard 15, as suspended by the coil spring 13', which moves downward the tread bar 14 and with it the shoe 6. The rod 13 connecting with the lever 10 mounted on the shaft 9 moves the lever 10 downward and at the same time moves the 95 lever 11 upward supporting the roller 12 which presses against the tapered edge of plate y and rolls under plate y held in position by key 4 on the underside of the shoe E and having a rolling contact therewith and 100 thus lifting plate y and shoe E upward as lever 11 moves upward the brake shoe D; and thus by one movement by pressure upon the footboard 15 I release both brake shoes C and D, the contact of roller 12 with plate 105 y giving a sudden and more extended lift to shoe E. The brakes C and D are thus completely released from the drive wheel B and the drive wheel revolves causing the hammer of the cutting machine to pass downward 110 and upward to its original position by one revolution of the drive wheel B. The upper

brake shoe D covering the outer surface of wheel B prevents oil or other substance from collecting on the same. It is to be noted that the drive wheel B revolves toward the front of frame A and therefore as the upper shoe comes down and presses upon the drive wheel B, shoe D being coupled to the under shoe C by means of the coil springs 6, 6 which draws the under shoe C the more tightly around wheel B. It is to be noted that I have mounted on the inner side of both brake shoes C and D the leather lining 7; this leather lining coming in contact with the surface of the drive wheel B pressed by the weight and pressure of the brakes C and D against the surface of the drive wheel B has a clinging grip effect upon the drive wheel holding it, when under the pressure of the brakes, in a firm, rigid position ready to be released for another movement of the cutter. Thus with each downward movement of the footboard 15 pressed by the foot, a single revolution of the drive wheel is made and one cutting movement made of the cutter; the foot of the operator being removed from the footboard 15 coil spring 13' brings the footboard to its original position; the brakes C and D drawn by the coil springs 6, 6 resume again instantly their normal position against the drive wheel B, holding it in a rigid position until it is desired to have the next operation made.

Having thus described my invention what I claim as new and for which I desire Letters Patent is as follows:

1. In a brake mechanism, the combination of an upper and a lower substantially semi-

circular brake shoe adapted to embrace a revolving part, said shoes being pivotally connected together at one end of each and resiliently connected at their other ends to normally maintain said shoes in applied position, a spring sustained treadle, a rocking lever for actuating one of said shoes, connecting means between said lever and the treadle for rocking said lever when the treadle is depressed, and other means between the treadle and the second brake shoe for actuating the latter, simultaneously with the first shoe to release the mechanism. 50

2. In a brake mechanism, the combination with a revoluble part, of an upper brake shoe, and a lower brake shoe embracing said revoluble part, said shoes being pivotally connected together at one end of each and resiliently connected at their other ends, to normally maintain said shoes in applied position about said revoluble part, one of said shoes having a radially projecting finger on its resiliently connecting end, a treadle, a spring sustaining said treadle, a rocking lever adapted to engage said finger, a connection between said treadle and said lever for raising one of said shoes through said finger when the treadle is depressed, and an independent connection between the treadle and the other shoe for releasing the same simultaneously with the first shoe. 55

In testimony whereof I have affixed my signature in the presence of two witnesses.

WILLIAM E. EDWARDS.
